UNITED STATES PATENT OFFICE

MICHAEL D. MURRAY, ZALMON GILBERT, AND LOT OSTROM, OF JOHNSTOWN, NEW YORK; SAID OSTROM ASSIGNOR TO SAID MURRAY AND GILBERT

DESIGN FOR GLOVE-BOXES.

Specification forming part of Design No. 8,051, dated February 9, 1875; application filed December 1, 1874.
[Term of Patent 3½ years.]

CASE A.

To all whom it may concern:

Be it known that we, MICHAEL D. MURRAY, ZALMON GILBERT, and LOT OSTROM, of Johnstown, in the county of Fulton and State of New York, have invented a Design for Glove-Boxes, "A," of which the following is a specification:

The nature of our design is fully represented in the accompanying photographic illustration, to which reference is made.

A represents the bottom of the box, cut to conform to the octagonal form of the rim B, which is also octagonal both in its interior and exterior surfaces. The two opposing sides where the braces or springs C C are attached are somewhat longer than the other six sides. The braces C C may be ornamented, as shown. The space represented at d is designed for the

transverse compression of the glove, and can be arranged therein, and in the compartments A A, to suit the fancy or requirement of the glove manufacturer.

What we claim as our invention is—

A design for a glove-box, in which the is octagonal, both as to its interior and exterior, two of whose opposite sides, to which the braces are attached, are longer than the other six, and ornamented, substantially in the manner above described and illustrated.

M. D. MURRAY.
ZALMON GILBERT.
LOT OSTROM.
